UNITED STATES PATENT OFFICE

THOMAS BRADFORD, OF ALLEGHENY, PENNSYLVANIA.

COMBINED FIRE-PLACE FENDER AND AIR-MOISTENER.

SPECIFICATION forming part of Letters Patent No. 376,575, dated January 17, 1883.

Application filed December 7, 1886. Serial No. 220,946. (No model.)

To all whom it may concern:

Be it known that I, THOMAS BRADFORD, a citizen of the United States, residing at Allegheny, in the county of Allegheny and State

5 of Pennsylvania, have invented certain new and useful Improvements in a Combined Fire-Place Fender and Air-Moistener; and I do hereby declare the following to be a full, clear, and exact description of the invention, such 10 as will enable others skilled in the art to which it pertains to make and use the same, reference being had to the accompanying drawings, which form a part of this specification.

My invention is an improvement in a combined fire-place fender and air-moistener, the 15 object being to provide a means whereby the atmosphere of a room or building may be moistened. This I accomplish by constructing a tank or vessel beneath the upper surface 20 of the fender, provided with one or more escape-pipes, whereby the steam generated by the heat of the fire may escape into the room, together with certain other details of construction and combination of parts, as will be fully 25 described hereinafter.

In the accompanying drawings, Figure 1 is a front elevation of my improved fire-fender and air-moistener constructed in accordance with my invention. Fig. 2 is a front sectional 30 elevation of the same. Fig. 3 is a side sectional elevation.

To put my invention into practice and give the same bodily form, I provide a fire-fender, *a*, of any well-known construction, and construct beneath the upper surface of the same a tank or vessel, *b*, which I partly fill with water *c* through an opening, *d*, provided with a close-fitting cap, *e*. At each end of this tank *b*, and in direct communication therewith, are 35 two pipes, *f*, provided with a hinged joint, *g*, and extending upward a short distance. These pipes *f* by means of the hinged joint *g* are capable of being revolved toward the fire-place when the same are not in active operation.

On the top to these pipes *f*, I place a perforated globe, *i*, through which the steam generated in the tank *b* may escape into the room.

In operation, water is placed in the tank *b* and the pipes *f* revolved toward the front of 50 the fender *a*. The heat from the fire-place radiating on the top of the fender *a* generates steam in the tank *b*, which, by means of the pipes *f*, escapes into the room through the perforated globe *i*, thereby moistening the same. 55

By the use of this combined fire-fender and air-moistener the heat of the fire regulates the quantity of moisture escaping into the room.

When it is desired to decrease the moisture of the room, one or both of the perforated 60 globes *i* are revolved directly in front of the fire-chamber, and by means of the natural draft of the chimney-flue the moisture escaping from the tank *b* is conducted or conveyed to the outside of the building. 65

By reference to an application which I have filed under date of January 24, 1887, Serial No. 225,387, it will be seen that I have shown therein a water-tank, pipes having hinge-joints for adjusting them with relation to the fire-place, and on top of these pipes perforated globes through which steam generated in the tank may pass. I therefore do not wish to claim such devices, broadly, in the present 70 application. 75

Having thus described my invention, what I claim, and desire to secure by Letters Patent, is--

The combination, with the fender *a*, of the water-tank below the upper surface thereof, a 80 outlet-feed-aperture provided with a cap, the outlet-pipes provided with a joint, and the adjustable evaporators, substantially as described.

THOMAS BRADFORD.
